UNITED STATES PATENT OFFICE

RALPH F. KNIGHT, OF BEVERLY, MASSACHUSETTS, ASSIGNOR TO UNITED SHOE MACHINERY CORPORATION, OF PATERSON, NEW JERSEY, A CORPORATION OF NEW JERSEY

MANUFACTURE OF HEELS

Application filed January 26, 1929. Serial No. 335,373.

This invention relates to methods of and apparatus for use in the measuring and the grading of heels. It is described and illustrated with particular reference to its application to grading wood heels and to measuring unattached heels of any description.

Heels possess a number of characteristics of which it is desirable to have exact or numerical measures, and it has heretofore been impossible to define these characteristics in numerical terms which will be uniformly understood by all makers and users of heels. The height of the heel is perhaps its most important quantitative characteristic, and there has been in the trade no definite idea of what the height of the heel means. The term is vaguely understood to be the height of the heel from the tread surface to the rim of the attaching face of the heel measured in a vertical plane at the breast but, except in the case of heels which have a vertical breast (and such heels, in the case of women's heels, at least, are not numerous), the term as so defined has little meaning, due to the fact that the attaching surface of the heel is generally on a considerable angle or pitch to the horizontal, herein for convenience termed the pitch angle, and the lack of any commonly accepted definition of where, in a fore and aft direction, the measurement is to be taken relatively to the curved breast causes a considerable indefiniteness in the determination of the height.

Other important data relating to the finished heel are the relative positions, longitudinally of the shoe, of the front and rear ends of the attaching surface and of the tread surface. In the case of any given heel these data and the height are all related to the angle discussed above; and any change in it alone will affect them all.

As suggested above, therefore, the principal difficulty in the determination of the desired characteristics of heels is in the absence of any fixed standard of height measurement and in the absence of any mechanism for rigorously determining the height according to any standard adopted. It is a principal object of the present invention to provide a method of measuring heels by the practice of

which, and a mechanism by means of which, the height as well as the other characteristics discussed above can be measured accurately and uniformly by any one in the case of a given heel; or compared in the case of different heels. 55

In the case of wood heels prior to the attachment of the top-lift, the height is measured from the top-lift receiving face, proper allowance being made for the thickness of the top-lift: In the case of leather heels or of finished wood heels the height is measured from the tread face of the top-lift. Herein the term "tread face" will be used generically to denote the surface from which the measurement is actually taken on heels of all types, proper allowance being made for the thickness of the top-lift in case this element is as yet missing from the heel. 60 65

According to the method of the present invention the height is to be measured vertically from the tread face, vertically to the edge or rim of the attaching face of the heel, in a vertical plane extending from one side of the heel to the other, the plane being perpendicular to the tread face and cutting the heel breast surface at an arbitrarily selected point which, as herein disclosed, is at a fixed distance (herein taken numerically as $\frac{3}{4}$ inch) below the intersection of the plane 70 75 with the edge of the attaching face of the heel. 80

In order to provide for the measurement of the heights of heels in accordance with this method I have provided a gaging apparatus comprising a part having a surface for engaging the tread face of a heel, a breast gage, and a member having a surface for engaging the attaching face of the heel. This member is pivotally mounted to provide for measuring the pitch angle. As illustrated, the two face engaging parts are adjustable toward and from each other to provide for measuring heels differing in height and, preferably, 85 90 suitable scales are provided, as will be shown, for indicating the height and pitch angle of a heel in the apparatus. Preferably also, scales are provided for measuring the positions of the front and rear points of the tread 95 100

face and of the attaching face relatively to some fixed point of the heel.

The structure above described comprises in effect a holding apparatus for heels which may constitute either a part of a device for measuring heels or comparing the characteristics of different heels or a part of a machine for forming the top-lift receiving surface. In the former case the tread face engaging member is a gage surface or member, in the latter case it is a tool constructed to form the top-lift receiving surface on an unfinished heel.

In accordance with an important feature of the invention, the pivotal axis of the pivotally mounted member is placed substantially in the surface engaging the attaching face of the heel, and the gage for the breast of the heel is located at the above-mentioned arbitrarily selected point, herein shown as at a fixed distance from the pivotal axis, and is located in a plane perpendicular to the surface engaging the tread face of the heel and passing through the said pivotal axis. Thus, as will be seen, a change in the pitch angle of the heel does not affect the measured height.

The pitch angle between the attaching surface and the horizontal, and the height, are established, during the manufacture of wood heels, in the so-called grading machine, which treats the heel blanks after they have had their breast, lateral and rear surfaces cut. At this time the attaching surface and the surface at the bottom end of the heel are in two parallel planes.

A grading machine, as heretofore constructed, consists of a saw and a pivotally mounted holder for an ungraded heel by means of which the heel can be swung past the saw and a generally wedge-shaped piece cut from its bottom end to form the top-lift receiving end and to determine the height. The holder is also angularly adjustable about an axis transverse to the heel and parallel to the saw, to determine the pitch angle. The location of the last-named pivotal axis has heretofore had no relation to the surfaces of a heel held in the holder, and consequently any change in the pitch angle produced by the machine has always altered the height and other characteristics of the heel, and a change in the pitch angle adjustment thus necessitated a corresponding change in the height adjustment. Consequently the obtaining of a given pitch angle and height has been a difficult and wasteful procedure.

In view of the foregoing, the present invention also provides a grading machine embodying the invention and organized to enable heels to be readily graded to the proper pitch and height, in accordance with the above method, thereby correcting the principal disadvantages of prior grading machines.

To this end, the illustrated grading machine comprises a tool, illustrated as a saw, and a pivotally mounted holder for a heel blank, having a pivotally adjustable attaching-face engaging surface against which the heel blank can be held and swung past the saw by means of a pivotal mounting for the holder itself, and a breast gage for the heel blank arranged in a plane passing through the pivotal axis of the attaching-face engaging surface and perpendicular to the saw. The illustrated holder, as a whole, is adjustable toward and from the saw. Thus a heel blank can be graded to any desired height and pitch angle, by one predetermined setting of the machine, in accordance with the above-described method and without troublesome complication of adjustments, as will be seen, and its characteristics can be checked or ascertained at any time by the maker or buyer by means of the gaging apparatus previously referred to.

These and other features of the invention comprising certain combinations and arrangements of parts will be apparent from the following description of a preferred embodiment of the invention shown in the drawings, in which

Fig. 1 is a perspective view of the gaging apparatus;

Fig. 2 is a plan view thereof and

Fig. 3 is an elevation thereof;

Fig. 4 is a perspective view of the grading machine;

Fig. 5 is a plan view thereof;

Fig. 6 is a detail view of the work holder; and

Fig. 7 is a detail of the adjusting mechanism.

The illustrated heel gaging or measuring apparatus (Fig. 1) has a frame having a base 10 and two parallel upstanding supports 12, 14 at the ends. A graduated bar 16 is mounted on the supports 12, 14, and on it is arranged to slide a frame 18 having an index 20 arranged to read on the graduations of the bar 16. The frame 18 has two parallel arms 22 between which, on two pivots 24, is mounted a flat plate 26, having a face 27 arranged to contact with the attaching face of a heel in the apparatus. The mounting is preferably formed of ears 28 to permit the pivotal axis of the pivots 24 to lie in the operative surface 27 of the plate 26. The plate 26 is adjustable about this pivotal axis and has an index 30, reading along a graduated arc 32 on the frame 18, by means of which the pitch angle of the attaching face of the heel can be read. The axis of the pivots 24 is perpendicular to the graduated bar 16.

The extremities of the arms 22 carry between them a gage member 34 parallel to the axis of the pivots 24. The operative edge 36 (Fig. 3) of this gage member is so arranged that the plane passing through it and the axis

of the pivots 24 will be parallel to the graduated bar 16 and perpendicular to the standard 12. The edge 36 of the gage member is, in the illustrated apparatus, located $\frac{3}{4}$ inch from the axis of the pivots 24.

If now, a heel 38 is placed with its tread face 40 in contact with the flat vertical side of the standard 12 and its breast surface in contact with the edge 36 of the gage bar 34, and the frame 18 moved along the bar 16 and the plate 26 rotated about the pivots at 24 until it contacts with the attaching face 42 of the heel, the heel 38 will just fit into the apparatus. The scale on the bar 16 is so arranged that the index 20 will read the height of the heel measured perpendicularly to the vertical face of the standard 12 through the edge 36 to the edge of the attaching face 42, at its intersection with the axis of the pivots 24. Thus the height of the heel is measured vertically from the tread face to the edge of the attaching surface through a point on the breast which is (in the present instance) $\frac{3}{4}$ inch vertically below the edge of the attaching surface, as is desired.

The standard 12 is provided with a graduated scale 44 with its zero in alignment with the pivotal axis of the screws 24 and the edge 36 of the gage bar 34, or in other words in a plane perpendicular to the standard 12 and passing through the axis at 24, 24, and the gage 36, and conveniently graduated in both directions from this zero. On this scale the positions of the front and rear points of the tread face 40 can be read relatively to this plane. The plate 26 is provided with a graduated scale 46 on which the position of the rear end of the attaching face 42 can be read, and a similar scale 48, graduated in the apparatus shown in eights of an inch, on which the position of the front edge of the attaching face can be read, relatively to this plane.

Fig. 4 shows a grading machine for wood heels by means of which heels having predetermined characteristics as above defined can be produced, and which also embodies the invention. A frame 50 supports a saw 52 driven by a motor 54. On the front part of the frame is supported a rotatable and slideable shaft 56. At one end the shaft is mounted in a plain bearing 58, and at the other end it is held by collars 60, 62 in a sleeve 64 the outside periphery of which is threaded into a member 66 mounted on the frame, is rotatable therein by a hand wheel 68 and is held in adjusted position by a clamp 70. Thus the shaft 56, while free to turn, can be longitudinally adjusted and its position read by an index 72 on the collar 62 against a scale 74 on the member 66.

Fixedly mounted on the shaft 56 is a work holder 76 having a heavy end 78 to turn it normally to a vertical position, out of engagement with the saw 52. The work holder is provided with an attaching face supporting

plate 80, corresponding to the plate 26, and similarly pivoted on the work holder 76 at 82. The plate 80 is provided with an index 84, and the holder with a graduated arc 86 by means of which the pitch angle can be set. A gage 88 is provided similar to the gage bar 34 with its gaging edge in a plane passing through the pivot 82 and perpendicular to the plane of the saw 52. The illustrated gage is at the same distance, $\frac{3}{4}$ inch, from the pivot 82, as in the case of the gage 36. The scale 74 and index 72 are so arranged that the scale will show the distance measured perpendicular to the saw 52 from the saw through the gaging edge 88 to the pivot 82 and the operative face of the plate 80, the theory being just the same as before.

In the use of the grading machine, the operator sets the indices 72 and 84 to the length and pitch angle desired, places the wood heel blank 90 against the plate 80 and the gage 88 as shown in Fig. 5, and swings it down past the saw with his left hand, holding it against the plate 80 with his left thumb, the shaft 56 rotating to permit the swing. This operation severs the little block 92, and, as it is termed, grades the heel.

A gage 94 (Fig. 6) is provided to assist the operator in holding the heel firmly in place and the plate 80 is angularly adjusted by a thumb wheel 96 and screw 98 having trunnion connections with the plate 80 and the work holder 76, as shown in exploded view in Fig. 7.

In a grading machine it is desirable that the finished work drop out of the work-holder as soon as the operator releases it, and therefore the ears 28 of the gaging apparatus above described have been omitted from the illustrated grading machine. The pivot 82, in the illustrated grading machine is therefore not quite in the operative surface of the plate 80, but the error resulting is negligible.

Having described my invention, what I claim as new and desire to secure by Letters Patent of the United States is:

1. That improvement in methods of making heels which consists in measuring the height of any heel perpendicularly to the tread face from the tread face to the edge of the attaching surface in a transverse plane which intersects the breast surface at a predetermined distance below the intersection of the said plane with the edge of the attaching surface.

2. In a grading machine for wood heels, a tool, and a work holder pivotally mounted on an axis perpendicular to the cutting plane of the tool and arranged to swing a heel past the tool, the holder having a surface arranged to contact with the attaching face of a heel in the work holder, said surface being pivotally adjustable about an axis parallel to the tool and extending from side to side of the heel and the axis of said pivotal

adjustment being in a plane perpendicular to the tool and intersecting the breast surface of the heel.

3. In a grading machine for wood heels, a saw, and a work holder pivotally mounted on an axis perpendicular to the plane of the saw and arranged to swing a heel past the saw, the holder having a surface arranged to contact with the attaching face of a heel in the work holder, said surface being pivotally adjustable about an axis parallel to the saw and extending from side to side of the heel and the axis of said pivotal adjustment being in the plane in which the height of the heel is measured.

4. In a grading machine for wood heels, a saw, and a work holder pivotally mounted on an axis perpendicular to the plane of the saw and arranged to swing a heel past the saw, said work holder being also adjustable along said axis, the holder having a surface arranged to contact with the attaching face of a heel in the work holder, said surface being pivotally adjustable about an axis parallel to the saw and extending from side to side of the heel, the axis of said pivotal adjustment being substantially in the plane of the attaching surface of the heel and also in a plane which is perpendicular to the saw and intersects the breast of the heel.

5. In a grading machine for wood heels, a saw, and a work holder pivotally mounted on an axis perpendicular to the plane of the saw and arranged to swing a heel past the saw, the holder having a surface arranged to contact with the attaching face of a heel in the work holder, said surface being pivotally adjustable about an axis parallel to the saw and extending from side to side of the heel, the axis of said pivotal adjustment being substantially in the plane of the attaching surface of the heel and also in a plane which is perpendicular to the saw and intersects the breast of the heel at a predetermined distance below the edge of the attaching face of the heel.

6. In a grading machine for wood heels, a saw, a work holder pivotally mounted on an axis perpendicular to the plane of the saw and arranged to swing a heel past the saw, the holder having a surface arranged to contact with the attaching face of a heel in the work holder, said surface being pivotally adjustable about an axis parallel to the saw and extending from side to side of the heel, the axis of said pivotal adjustment being in a plane perpendicular to the saw and intersecting the breast surface of the heel, and a gage for contacting with the breast of the heel.

7. In a grading machine for wood heels, a saw, a work holder pivotally mounted on an axis perpendicular to the plane of the saw and arranged to swing a heel past the saw and being also adjustable along the

said axis, the holder having a surface arranged to contact with the attaching face of a heel in the work holder, said surface being pivotally adjustable about an axis parallel to the saw and extending from side to side of the heel, the axis of said pivotal adjustment being in the plane in which the height of the heel is measured, and a gage for contacting with the breast of the heel, said gage being located in the said plane.

8. In a grading machine for wood heels, a saw, a work holder pivotally mounted on an axis perpendicular to the plane of the saw and arranged to swing a heel past the saw, the holder having a surface arranged to contact with the attaching face of a heel in the work holder, said surface being pivotally adjustable about an axis parallel to the saw and extending from side to side of the heel, the axis of said pivotal adjustment being substantially in the plane of the attaching surface of the heel and also in a plane which is perpendicular to the saw and passes through the breast of the heel, and a gage for contacting with the breast of the heel, said gage being located in the last-mentioned plane.

9. In a grading machine for wood heels, a saw, a work holder adjustable toward and from the saw and pivotally mounted on an axis perpendicular to the plane of the saw and arranged to swing a heel past the saw, the holder having a surface arranged to contact with the attaching face of a heel in the work holder, said surface being pivotally adjustable about an axis parallel to the saw and extending from side to side of the heel, the axis of said pivotal adjustment being substantially in the plane of the attaching surface of the heel and also in a plane which is perpendicular to the saw and passes through the breast of the heel, and a gage for contacting with the breast of the heel, said gage being located in the last-mentioned plane and at a predetermined distance from the intersection of this plane with the surface which contacts with the attaching face of the heel.

10. In a measuring apparatus for heels, a member having a surface for contacting with the tread face of a heel in the apparatus, a member having a surface for contacting with the attaching face of the heel, said members being relatively adjustable angularly and toward and from each other to fit different heels, a member located between the said surfaces to determine the position of the heel between the surfaces, and measuring scales for ascertaining the heights and pitch angles of heels fitted into the apparatus.

11. In a measuring apparatus for heels, a part having a surface for contacting with the tread face of a heel in the apparatus, a part having a surface for contacting with the at-

taching face of the heel, said parts being relatively angularly adjustable and relatively movable toward and from each other to accommodate heels of different heights and pitch angles, a member located between the said surfaces to determine the position of the heel between the surfaces and thereby to determine the distance of the surfaces from each other when in contact with a particular heel, and indicating apparatus for showing the height and pitch angle of the heel.

12. In a measuring apparatus for heels, a member having a surface for contacting with the tread face of a heel in the apparatus, a member having a surface for contacting with the attaching face of the heel, said members being relatively angularly adjustable about an axis and relatively movable toward and from each other to accommodate heels of different heights and pitch angles, means for indicating the angle between the said surfaces, and means for indicating their distance measured through the axis of the said angular adjustment.

13. In a measuring apparatus for heels, a member having a surface for contacting with the tread face of a heel in the apparatus, a member having a surface for contacting with the attaching face of the heel, said surfaces being relatively angularly adjustable about a pivotal axis and relatively movable toward and from each other to accommodate heels of different heights and pitch angles, means for indicating the angle between the said surfaces, means for indicating their distance measured through the pivotal axis of the said angular adjustment, and perpendicular to the tread face engaging surface, and a gage for contacting with the breast of a heel in the apparatus.

14. In a measuring apparatus for heels, a surface for contacting with the tread face of a heel in the apparatus, a member having a surface for contacting with the attaching face of the heel, said surfaces being relatively angularly adjustable about a pivotal axis lying in one of the surfaces and relatively movable toward and from each other to accommodate heels of different heights and pitch angles, means for indicating the angle between the said surfaces, means for indicating their distance measured through the pivotal axis of the said angular adjustment, and a gage for contacting with the breast of a heel in the apparatus, said gage being located in a plane which passes through the said pivotal axis and is perpendicular to the tread face of a heel in the apparatus.

15. In an apparatus for measuring heels, a surface arranged to contact with the tread surface of a heel in the apparatus, a graduated bar at right angles to the said surface, a frame having an index arranged to slide along the bar, with the index reading along the graduation thereof, a plate pivoted in said

frame on an axis parallel to the said surface and arranged to contact with the attaching face of the heel, and a graduated scale arranged to show the angular position of said plate, when in contact with the heel.

16. In an apparatus for measuring heels, a surface arranged to contact with the tread surface of a heel in the device, a graduated bar at right angles to the said surface, a frame having an index arranged to slide along the bar, with the index reading along the graduation thereof, and a plate pivoted in said frame on an axis parallel to the said surface and arranged to contact with the attaching face of the heel, the said axis lying substantially in that face of the plate which contacts with the attaching face of the heel.

17. In an apparatus for measuring heels, a surface arranged to contact with the tread surface of a heel in the device, a graduated bar arranged transversely to the said surface, a frame having an index arranged to slide along the bar, with the index reading along the graduation thereof, a plate pivoted in said frame on an axis parallel to the said surface and arranged to contact with the attaching face of the heel, the said axis lying substantially in that face of the plate which contacts with the attaching face of the heel, and a gage arranged to contact with the breast of the heel.

18. In an apparatus for measuring heels, a surface arranged to contact with the tread surface of a heel in the device, a graduated bar at right angles to the said surface, a frame having an index arranged to slide along the bar, with the index reading along the graduation thereof, a plate pivoted in said frame on an axis parallel to the said surface and arranged to contact with the attaching face of the heel, the said axis lying substantially in that face of the plate which contacts with the attaching face of the heel, and a gage arranged to contact with the breast of the heel, said gage being located in a plane which passes through the said pivotal axis and which is also perpendicular to the first-mentioned surface.

19. In a measuring apparatus for heels, a surface for contacting with the tread face of a heel in the apparatus, a surface for contacting with the attaching face of the heel, said surfaces being relatively angularly adjustable and relatively movable toward and from each other to accommodate heels of different heights and pitch angles, a gage for positively locating the heel in the apparatus, and graduations on the attaching face engaging surface whereby the positions of the rear and front ends of the attaching face relatively to the gage can be ascertained.

20. In a measuring apparatus for heels, a surface for contacting with the tread face of a heel in the apparatus, a surface for contacting with the attaching face of the heel, said

surfaces being relatively angularly adjustable about a pivotal axis and relatively movable toward and from each other to accommodate heels of different heights and pitch angles, and graduations on the attaching face 5 engaging surface having their zero at the said pivotal axis whereby the positions of the rear and front ends of the attaching face can be ascertained relatively to the said pivotal axis.

21. In a measuring apparatus for heels, a surface for contacting with the tread face of a heel in the apparatus, a surface for contacting with the attaching face of the heel, said surfaces being relatively angularly adjustable about a pivotal axis and relatively movable toward and from each other to accommodate heels of different heights and pitch angles, and a scale adjacent to the first-named surface whereby the positions of the rear and front ends of the tread face of the heel can be ascertained relatively to the said pivotal axis.

22. In a measuring apparatus for heels, a surface for contacting with the tread face of a heel in the apparatus, a surface for contacting with the attaching face of the heel, said surfaces being relatively angularly adjustable about a pivotal axis and relatively movable toward and from each other to accommodate heels of different heights and pitch angles, and a scale adjacent to the first-named surface whereby the positions of the rear and front ends of the tread face of the heel can be ascertained relatively to the said pivotal axis, said scale having a zero in a plane which is perpendicular to the said first-named surface and which passes through the said pivotal axis.

23. An apparatus for holding heels comprising a member having a surface for contacting with the attaching face of a heel, said member being angularly adjustable about an axis lying substantially in the said surface, a second member having a fixed position and having a surface for contacting with the tread face of the heel, said first-named member being adjustable toward and from said member in the fixed position to accommodate heels of varying heights, and a gage for the breast of the heel, located in the plane passing through the said axis and perpendicular to the surface in the fixed position.

24. In a grading machine for wood heels, a saw for forming the tread face of a heel in the machine, a member movable relatively to the saw in a direction parallel to the plane of the saw and having a surface for contacting with the attaching face of the heel, the saw and the member being relatively angularly adjustable and relatively movable toward and from each other to impart different heights and pitch angles to different heels, means for indicating the angle between the saw and the surface, means for indicating their distance measured through the pivotal axis of the said

adjustment, and a gage for contacting with the breast of a heel in the apparatus, said gage being located in a plane which passes through the said pivotal axis and is perpendicular to the plane of the saw.

25. An apparatus for holding heels comprising a member, a heel holding and gaging device adjustable along said member, an indicating device comprising a graduated scale and pointer one of which is carried by the said member and the other of which is carried by the holding and gaging device, for indicating the extent of the said adjustment, and arranged to indicate the distance of a certain point on the holding and gaging device from a plane having a fixed location relatively to that member of the indicating device that is carried by the first said member, the holding and gaging device having an element pivotally mounted thereon at the said point on an axis perpendicular to the first said member, the element having a surface for contacting with the attaching face of a heel held in the apparatus, and a gage for the breast of the heel located in a plane passing through the said pivotal axis and parallel to the said member.

In testimony whereof I have signed my name to this specification.
